CLAIM

The ornamental design for a preparation station, as shown and described.

DESCRIPTION

FIG. 1 is a front, right perspective view of a preparation station.

FIG. 2 is a front, right perspective view of a grate of the preparation station of FIG. 1.

FIG. 3 is a front, right perspective view of a platform of the preparation station of FIG. 1, shown in an exploded configuration.

FIG. 4 is a front elevation view of the preparation station of FIG. 1.

FIG. 5 is a rear elevation view of the preparation station of FIG. 1.

FIG. 6 is a right-side elevation view of the preparation station of FIG. 1.

FIG. 7 is a left-side elevation view of the preparation station of FIG. 1.

FIG. 8 is a top plan view of the preparation station of FIG. 1.

FIG. 9 is a bottom plan view of the preparation station of FIG. 1.

FIG. 10 is a front, right perspective view of the preparation station of FIG. 1, shown in use within a cabinet.

FIG. 11 is a front, right perspective view of the preparation station of FIG. 1, shown in use within a cabinet with a preparation pan; and,

FIG. 12 is a front, right perspective view of the preparation station of FIG. 1, shown in an exploded configuration with a cabinet and a preparation pan.

Exhibit A is a series of figures for an alternative embodiment of the preparation station, cabinet, and preparation pan.

Exhibit B is a promotional presentation.

Exhibit C is a series of detailed specifications.

The broken lines showing a cabinet and preparation stand are for the purpose of illustrating environment and form no part of the claim.

Shading forms no part of the claim.

1 Claim, 9 Drawing Sheets
